UNITED STATES PATENT OFFICE.

GEORGE W. MORSTATT, OF NEW YORK, N. Y.

IMPROVEMENT IN CHAIRS.

Specification forming part of Letters Patent No. 124,281, dated March 5, 1872.

To all whom it may concern:

Be it known that I, GEORGE W. MORSTATT, of New York, in the county and State of New York, have invented certain Improvements in Chairs, of which the following is a specification:

The nature of my invention consists in the arrangements of levers connecting the upper and lower part of a chair to enable the seat to be raised or lowered, whereby a square or four-legged chair or a double-seated piano-chair can be made without any suspended screw in the central part.

In the accompanying drawing, Figure I represents a cross-section of a chair embodying my invention. Fig. II represents the same view with the seat raised upward. Fig. III shows a longitudinal section of the same; and Fig. IV is a plan with the seat removed.

B is the lower frame, having at each corner legs L attached. A is the top frame with the cushion or seat attached. CC are levers crossing each other and attached through the pins *a a* to the upper and lower frames A and B, capable of turning on said pins *a*. The other ends, *n*, of said levers CC work in longitudinal slots *m m* arranged in the upper frame A and in the lower frame B. To the center of these levers CC a segment, D, is attached, provided on one side with teeth *x*, into which pawls *w* fit, acted upon by suitable springs *v*. (See Fig. IV.) By this arrangement the upper seat

A can be moved upward or downward in any desired position, and supported at the desired heights by the action of the pawls *w* in the corresponding tooth *x* on the rack or segment D. The pawls *w* are connected through the links *o o*, (see Fig. IV,) with a lever, *z*, reaching toward the front part of the chair, whereby the said pawls can be moved away, clear of the teeth *x* in the segment D, when the seat A requires to be raised or lowered, and said pawls *w* are moved back again or forced into the teeth *x* by the action of their springs *v*.

By this arrangement a square, oval, or any other desired-shape chair can be made without the necessary fixings required where a central screw is used for raising or lowering the seat; and at the same time a double-seated chair can be divided in two parts, where each part or seat can be raised or lowered independent of the other part or seat.

What I claim as my invention, and desire to secure by Letters Patent, is—

The arrangement of the levers CC, segments D, pawls *w w*, in connection with the lever *z*, when combined with the upper and lower part of a chair, substantially as and for the purpose hereinbefore set forth.

GEO. WM. MORSTATT.
